US0D1000736S

(12) **United States Design Patent** (10) Patent No.: **US D1,000,736 S**
(45) Date of Patent: ** Oct. 3, 2023

(54) **DELIVERY MODULE FOR WASHING MACHINE**

(71) Applicant: **Wuxi Little Swan Electric Co., Ltd.**, Jiangsu (CN)

(72) Inventors: **Wenjing Liao**, Jiangsu (CN); **Weijia Wang**, Jiangsu (CN)

(73) Assignee: **Wuxi Little Swan Electric Co., Ltd.**, Jiangsu (CN)

(**) Term: **15 Years**

(21) Appl. No.: **35/514,871**

(22) Filed: **May 5, 2022**

(80) **Hague Agreement Data**

Int. Filing Date: **May 5, 2022**

Int. Reg. No.: **DM/222380**

Int. Reg. Date: **May 5, 2022**

Int. Reg. Pub. Date: **Aug. 5, 2022**

(30) **Foreign Application Priority Data**

Dec. 1, 2021 (CN) 202130795148.X
